J. G. BALSILLIE.
REFLECTOR FOR USE IN LIGHT PROJECTORS.
APPLICATION FILED NOV. 16, 1920.

1,390,747.

Patented Sept. 13, 1921.

UNITED STATES PATENT OFFICE.

JOHN GRAEME BALSILLIE, OF MELBOURNE, VICTORIA, AUSTRALIA, ASSIGNOR TO FLATLITE LIMITED, OF SYDNEY, NEW SOUTH WALES, AUSTRALIA, A CORPORATION OF NEW SOUTH WALES.

REFLECTOR FOR USE IN LIGHT-PROJECTORS.

1,390,747.

Specification of Letters Patent. Patented Sept. 13, 1921.

Application filed November 16, 1920. Serial No. 424,530.

To all whom it may concern:

Be it known that JOHN GRAEME BALSILLIE, subject of the King of Great Britain, residing at Collins House, 360-366 Collins 5 street, Melbourne, Victoria, Australia, has invented certain new and useful Improvements in Reflectors for use in Light-Projectors, of which the following is a specification.

10 This invention relates to improvements in reflectors for use in light projectors more particularly adapted for the headlamps of vehicles such as motor cars and the like.

Though this invention is herein described 15 as being adapted for the headlamps of motor cars, it will be understood that it is applicable for the head lights of locomotives, trams, and the like, and is also adaptable for the projection of light for other purposes such as street lighting.

It is known that when a roadway in front 20 of a road vehicle is brilliantly illuminated by non-diffused light, the driver or an observer has great difficulty in seeing objects 25 immediately beyond the area of bright illumination. The reason for this is that the brilliantly illuminated path of roadway interferes with the resolving power of the eye. It has long been known that more 30 satisfactory road illumination can be achieved by diffused lighting but hitherto this type of illumination has been usually characterized by glare which interferes with the vision of persons looking toward the source 35 of light.

The object of the present invention is to provide means whereby light may be diffusely reflected and projected preferably in a beam of elliptical cross section substantially.

40 I accomplish this object by providing the reflecting surface of a reflector with configurations which function to reflect light diffusely in one plane and substantially 45 regularly in the plane at right angles thereto.

This is effected by providing the reflecting surface of the reflector with parallel corrugations, grooves, or furrows.

When such configurations are applied to 50 the reflecting surface of a stigmatic reflector such as a parabolic or a spherical reflector, and a source of light is placed at the focal point thereof, diffused light is projected in relatively parallel rays in one 55 plane and divergent or convergent divergent rays in the plane at right angles thereto.

When such configurations are applied to 60 the reflecting surface of a regularly astigmatic reflector parallel with one or other of the chief meridians and a source of light is placed at or about the focal point of that chief meridian with which the configurations are parallel diffused light is projected 65 in relatively parallel rays in one plane, and divergent or convergent divergent rays in the plane at right angles thereto.

When such configurations are applied to 70 the reflecting surface of an astigmatic reflector, preferably at right angles to its principal meridian and a source of light is placed at or about the focal point of the shortest principal meridian light is projected in relatively parallel rays in the 75 plane of one meridian and divergent or convergent divergent rays in the plane of the other meridian.

The plane in which the light is projected 80 in substantially parallel rays coincides with the plane of that meridian of the reflector with which the said configurations are parallel.

The type of configuration that I find most 85 satisfactory is regularly parallel corrugations, furrows, or grooves, which may be of varying frequency and radius, but preferably of about 35 to an inch, each corrugation having a radius of curvature of seven thirty seconds of an inch. In this specification, the term "corrugations" will be understood to include furrows or grooves. These corrugations made on the reflecting surface function to give a regularly astigmatic effect to a stigmatic reflector. When 90 the invention is adapted to a regular astigmatic reflector the corrugations are made parallel with one or other of the principal 95

meridians, and may function to accentuate the inherent astigmatism. By varying the radius of these corrugations and their frequency, the degree of divergence can be altered to suit different conditions.

In order that this invention may be the better understood, I will now proceed to describe same by reference to the accompanying sheet of drawings, in which,

10 Figure 1 is an elevation, and

Fig. 2 a cross section of a regularly astigmatic reflector which has been configurated in accordance with this invention, such configurations being in the form of corrugations parallel to the smallest principal meridian.

Fig. 3 is a vertical sectional elevation of a motor head lamp fitted with a reflector as shown in Figs. 1 and 2.

20 Fig. 4 is a front elevation of a stigmatic parabolic reflector as ordinarily in use which has been configurated in accordance with this present invention such configurations being in the form of parallel corrugations.

25 Figs. 5, 6, and 7, are sections of a portion of a reflector to which corrugations of different configurations have been applied for the purpose of this invention.

30 In these drawings A represents the reflector within which is fitted the source of light B (such as an electric lamp) adapted to fit within the socket C.

35 In Figs. 1, 2, and 3, a regular astigmatic reflector is shown, and this may be mounted within the ordinary head lamp of the vehicle as shown in Fig. 3.

40 For the purpose of this present invention the reflecting surface of the reflector A is figured with a series of parallel corrugations, which function to diffusely reflect light.

45 Obviously the curvature of the reflector and the location of the source of light determines, to a certain extent, the shape of the cross section of the projected beam because the corrugations only operate to diverge the light projected in a plane at right angles to the plane of the corrugations. The 50 source of light should be located at or about the focal point of that meridian of the reflector which is parallel with the plane of the corrugations.

55 The corrugations are made parallel with one of the chief meridians of the reflector and may be made to function to accentuate the astigmatism. By varying the radius of these corrugations and their frequency, the amount of divergence can be altered to suit 60 different conditions. For example, satisfactory results have been obtained with corrugations in which the radius of curvature

and frequency have been of the following dimensions:—

Curvature radius in inches.	Frequency per inch.	65
Seven thirtyseconds.	Thirtyfive.	
Twelve thirtyseconds.	Fifteen.	
Ten thirtyseconds.	Twentyfive.	70
Six thirtyseconds.	Fortyfive.	

The invention is applied in a similar manner to reflectors of all types wherein all meridians are curves by configuring the reflecting surface as shown in Fig. 4 with a 75 series of parallel corrugations.

In astigmatic reflectors the corrugations are preferably at right angles to the principal meridian. The corrugations may be concaval as shown in Fig. 5 or convexo-concaval as shown in Fig. 6, or in the form of V shaped depressions as shown in Fig. 7.

I claim:—

1. A reflector having its reflecting surface provided with parallel corrugations arranged to project light in relatively parallel rays in one plane and divergent rays in the plane at right angles thereto.

2. A reflector for use in light projectors having its reflecting surface provided with 90 corrugations parallel with one meridian.

3. A reflector for use in light projectors in which all the meridians are curves of graduating focal lengths having its reflecting surface provided with corrugations at 95 right angles to the principal meridian.

4. A reflector for use in light projectors in which all the meridians are curves of graduating focal lengths and in which the chief meridians are mutually at right angles 100 and the values of the intermediate semi-curves in each quadrant decreases uniformly from the largest to the smallest having its reflecting surface provided with corrugations parallel with one of the said chief 105 meridians.

5. In light projectors, a reflector having the reflecting surface provided with corrugations parallel with one meridian and a source of light placed at or about the focal 110 point of that meridian.

6. In head lamps for vehicles, a reflector having its reflecting surface provided with corrugations arranged with the planes of the corrugations substantially perpendicular 115 to the surface of the roadway and parallel with one meridian.

In testimony whereof he has affixed his signature in the presence of two witnesses.

JOHN GRAEME BALSILLIE.
